CYCLOMETER CLOCK AND CARRY-OVER
MECHANISM

Lucien C. Wuischpard, Long Hill, Conn., assignor
to Casco Products Corporation, Bridgeport,
Conn., a corporation of Connecticut

Application October 12, 1946, Serial No. 702,983

6 Claims. (Cl. 235—143)

1

This invention relates to cyclometer-type clocks and to carry-over mechanisms for such clocks.

An object of the invention is to provide in a cyclometer clock an improved registering and carry-over mechanism the component parts of which are extremely simple, economical to fabricate and easy to assemble, and the mechanism as a whole being reliable and positive in its operation.

Another object of the invention is to provide an improved cyclometer-type clock having a registering and carry-over mechanism as above, the said clock and mechanism being so arranged that the indicia-carrying members thereof are easily and quickly adjusted or set.

A feature of the invention is the provision, in a clock, of extremely simple structures so organized and related as to produce a reliable, yet small and compact cyclometer-type timepiece.

Other features and advantages will hereinafter appear.

In the accompanying drawings:

Figure 1 is a sectional view of a clock with registering and carry-over mechanism made according to the invention, the casing of the clock being shown in vertical section, and the interior mechanism of the clock being shown in front elevation.

Fig. 2 is a view like Fig. 1, but with the indicating members of the clock mechanism shown in vertical section, the section being taken in a plane located just ahead of the supporting shaft for the members and the members being set differently from their positions of Fig. 1, and being located in such position that all are connected together for simultaneous movement or advance, as occurs at 12:59:55 for instance. The positions of the members immediately at the termination of such advance, wherein 1:00 o'clock is indicated, is shown in Fig. 1.

Fig. 3 is a vertical transverse section taken on the line 3—3 of Fig. 2.

Fig. 4 is a vertical transverse section taken on the line 4—4 of Fig. 2.

Fig. 5 is a vertical transverse section taken on the line 5—5 of Fig. 2.

Fig. 6 is a vertical transverse section taken on the line 6—6 of Fig. 2.

Fig. 7 is a vertical transverse section taken on the line 7—7 of Fig. 2.

Fig. 8 is a fragmentary detail, showing on an enlarged scale the lower end of the leaf springs provided on the "minutes" and also provided on the "tens of minutes" indicating members

2

of the clock, the said leaf springs constituting important component parts of the carry-over mechanism.

Fig. 9 is a section taken on the line 9—9 of Fig. 8, and

Fig. 10 is a view like Fig. 8, but of the leaf spring associated with the "seconds" member of the clock.

As shown, the clock with improved registering and carry-over mechanism of the invention comprises a casing 10 having a top 11, end walls 12 and 13, and front and rear walls 14 and 15, respectively. The casing 10 is shown as being rectangular or oblong in shape, although it should be understood that it may have other shapes for purposes of styling, to facilitate its fabrication, etc.

The casing 10 has a bottom 16 which is preferably separate from the side and end walls, and which may be secured to the said walls in any suitable, desired manner.

For the purpose of mounting the mechanism of the clock within the casing 10 a U-shaped metal bracket 17 is provided, having upstanding arms 18 and 19 which are integral with a yoke or bottom plate 20, the latter being secured to the bottom 16 of the casing by suitable means such as screws 21.

The arms 18 and 19 of the bracket 17 are apertured to receive and rotatably carry a shaft 22, Fig. 2, the said shaft having rigidly secured to one end a gear wheel 23 at the outside of the bracket arm 19, and carrying a spacer collar 24 at the inside of the arm 19.

The shaft 22 mounts a plurality of drums 25, 26, 27 and 28, the drum 25 constituting the "hour" drum of the clock, the drum 26 the "tens of minutes" drum, the drum 27 the "minutes" drum, and the drum 28 the "seconds" drum of the clock, and the latter drum being rigidly secured to the shaft 22 to be rotatable therewith at all times.

Referring to Figs. 1 and 3, the "hour" drum 25 has 12 flat faces 29 equally spaced about its periphery, making it polygonal in shape, the said faces respectively carrying numbers from "1" to "12" inclusive, in consecutive order.

As seen in Figs. 1 and 4, the "tens of minutes" drum 26 also has 12 flat faces, designated 30, which are equally spaced about its periphery in the same manner as the drum 25. However, the faces 30 of the drum 26 carry numbers reading consecutively from "0" through "5," this sequence being repeated so that there are two series of 55 such numbers in all. The "minutes" drum 27,

as shown in Figs. 1 and 5, has 10 flat faces 31 equally spaced about its periphery, the said faces respectively having the numbers from "0" through "9." The "seconds" drum 28 is shown as having a cylindrical peripheral surface 32, and this surface may be provided with numbers and/or graduations (not shown), indicating seconds from "1" to "60," as is common practice in cyclometer clocks.

For the purpose of motivating the drums of the clock an electric motor 33 is provided, mounted on a plate 34 which is secured to the upstanding arm 19 of the bracket 17 and is spaced therefrom by spacers 35. The motor 33 has a drive spindle 36 carrying a pinion 37 which engages a gear wheel 38 mounted on a jack shaft 39, the latter also mounting a pinion 40 engaging the gear wheel 23 on the main shaft 22 of the registering mechanism. By this organization the motor 33 drives the shaft 22 through gear reduction, and at such a speed that the shaft 22 makes one revolution in each minute.

The indicia-carrying drums 25, 26 and 27 are loose on the shaft 22, and are rotatable independently of the shaft, and therefore the motor 33 drives only the "seconds" drum 28 with a continuous rotary movement. As shown in Fig. 2, the drums 25, 26, 27 and 28 are spaced from each other by hubs 26a, 27a and 28a of the latter three drums, which hubs are sufficiently long to extend a slight distance beyond the corresponding peripheral side edges of the drums, and to engage adjacent drums. The "hours" drum 25 has a hub 25a which extends beyond its corresponding peripheral side edge and engages the inner face of the upstanding arm 18 of the bracket 17. By this arrangement, due to the fact that the "seconds" drum 28 is secured rigidly to the shaft 22, and is located between the bracket arms 18 and 19, the shaft 22 is prevented from having endwise movement in either direction in the bracket 17.

As shown in Figs. 1, 3, 4, and 5, the flat faces of the drums 25, 26 and 27 have concave cutouts 41 which cooperate with leaf springs 42 mounted on an upstanding flange 43 of the bracket 17, the said cutouts and leaf springs providing a complementary drive and detent action for the drums to maintain the foremost-located flat faces thereof in registration with each other at all times.

According to the present invention an improved, simple and reliable carry-over mechanism is provided, associated with the drums of the clock to cause these to be intermittently moved or driven in a certain predetermined order in response to turning of the "seconds" drum 28 so that the indicia of the drums will indicate the correct time. This carry-over mechanism includes a pair of carry-over pins 44 slidably carried by the "tens of minutes" drum 26 on opposite peripheral portions thereof, the pins 44 being parallel with the spindle 22. A third carry-over pin 45 is slidably carried in a peripheral portion of the "minutes" drum 27 and is so located that, upon proper positioning of the "minutes" drum with respect to the "tens of minutes" drum 26 the pin 45 will align itself with either one of the pins 44. A fourth carry-over pin 46 is also provided, slidably mounted in a peripheral portion of the "seconds" drum 28 so as to be parallel with the shaft 22, and the location of the pin 46 is such that it may be brought into registration with the pin 45 upon properly positioning the drum 28 with respect to the drum 27.

For the purpose of controlling the axial posi-

tions of the pins 44, 45 and 46, these are provided each with an annular groove 47 adjacent one end.

Referring to Figs. 2 and 6, the drum 28 has a groove 48 in one face in which is disposed a leaf spring 49 anchored at one end 50 to the drum by a pin 51. The other end 52 of the leaf spring 49 is bifurcated and is received in, and slidable in the groove 47 of the carry-over pin 46. Referring to Fig. 5, the "minutes" drum 27 has a groove 53 in which is carried a leaf spring 54, one end 55 of which is anchored to the drum by a pin 56. The other end of the leaf spring 54 has a folded back tip portion 57 which is spaced from the spring a slight amount and is provided with a cut or slot having a short wide portion 58 and a longer and narrower portion 59. The width of the slot portions 58 and 59, and their locations are such, as shown in Fig. 8, that the grooved end portion of the carry-over pin 45 may be fitted within the end of the leaf spring, the groove of the said portion slidably accommodating the edges of the narrow slot portion 59 and the end of the pin-engaging the folded tip portion 57 of the leaf spring.

Referring to Figs. 2 and 4 the "tens of minutes" drum 26 has a pair of grooves 60 in one face which accommodates leaf springs 61 anchored at their ends 62 to the drum, the springs at their opposite ends having folded-over tip portions 63 similar to the folded tip portion 57 of the spring 54. The leaf springs 61 at their folded ends engage the carry-over pins 44 in the same manner as that shown in Figs. 8 and 9 with respect to the spring 54 and the carry-over pin 45.

According to this construction the carry-over pins 44, 45 and 46 are freely slidable axially except for the restraint imposed on them by the associated leaf springs, and such restraint is of a true yielding nature without binding, within the operative limits of movement of the pins. The leaf springs 61 carried by the "tens of minutes" drum 26, and the leaf spring 54 carried by the "minutes" drum 27 are biased so that normally they yieldably hold the carry-over pins 44 and 45 in axial positions wherein the remote ends 44a and 45a of the pins are substantially flush respectively with the peripheral side edges 26b and 27b of the associated drums. Also, the leaf spring 49 carried by the "seconds" drum is biased to normally yieldably hold the remote end 46a of the carry-over pin 46 substantially flush with the peripheral side edge 28b of the drum 28.

For cooperation with the pins 44 of the carry-over mechanism the "hour" drum 25 is provided with a plurality of radial ribs or ledges 64, Figs. 2 and 3, formed by providing recesses 65 in one face of the drum.

Referring to Fig. 2 when either of the carry-over pins 44 is in an extended position as shown, the remote end 44a thereof will engage one of the radial ribs 64 so that upon rotation of the "tens of minutes" drum 26 the latter will carry with it the "hour" drum 25 until such time as the extended or projected carry-over pin 44 is again retracted and the remote end 44a thereof is flush with the peripheral side edge 26b.

Similarly the "tens of minutes" drum 26, see Figs. 1 and 4, is provided with a plurality of radial ribs 66 for engagement and cooperation with the carry-over pin 45 when the latter is in its extended position as shown in Fig. 2. The "minutes" drum 27, referring to Figs. 2 and 5, also has radial ribs 67 cooperable with the carry-over pin 46 when the latter is in the extended position of Fig. 2.

It will be noted that the number of radial ribs 64 in the "hour" drum 25 corresponds with the number of flat faces 29 of the said drum and are respectively normal to the said faces. The same is true of the radial ribs 66 in the "tens of minutes" drum 26, with respect to the flat faces 30 of the drum.

Referring to Fig. 5, the radial ribs 67 of the drum 27 are ten in number, each rib being aligned with the line of intersection of a different adjacent pair of flat faces 31. It will also be noted that the carry-over pins 45 are located adjacent but on opposite sides of a diametric pair of radial ribs 66 as shown in Fig. 4. The carry-over pin 45 in the drum 27, as seen in Fig. 5, is located adjacent one of the radial ribs 67 of the drum.

The carry-over pins 44, 45 and 46, and the leaf springs 54 and 61 are so arranged that, when three of the carry-over pins are in alignment or in registration, as shown in Fig. 2, axial movement of the carry-over pin 46 to cause the remote end 46a thereof to project from the side of the drum 28, will simultaneously axially shift the carry-over pins 44 and 45 so as to cause the remote ends 44a and 45a of these pins to also project from the sides of their respective drums, and in such circumstance turning of the "seconds" drum 28 will cause simultaneous turning of the three other drums 25, 26 and 27 by virtue of the engagement of the remote ends of the carry-over pins with the cooperable radial ribs of the drums. If only two of the pins, namely the pins 45 and 46, are in registration at the time the pin 46 is shifted axially in the manner described, then turning of the "seconds" drum 28 will result in turning of only the two drums 26 and 27. If the carry-over pins 44 and 45 are both out of registration with the carry-over pin 46 at the time that the latter is shifted axially, then rotation of the "seconds" drum 28 will cause simultaneous rotation of only the "minutes" drum 27.

By this organization it is possible to intermittently advance the drums of the registering mechanism in a certain predetermined order so as to correctly indicate the time, by properly arranging to axially shift the carry-over pin 46 of the "seconds" drum 28 once in each revolution of the latter, and for a small fractional portion of a revolution, the said shifting occurring immediately prior to the drum 28 reaching the position shown in Figs. 2 and 6, and the direction of rotation of the drum being indicated by the arrow in the latter figure. In accomplishing this axial shifting of the carry-over pin 46 automatically, there is provided a cam strip 67, Figs. 2 and 7, the said strip being lanced from the upstanding arm 19 of the U bracket 17, and having a sloping camming surface 68 and a flat high spot 70. Upon the "seconds" drum 28 reaching a position immediately prior to that shown in Figs. 2 and 6, the projecting end 71 of the carry-over pin 46 will engage the camming surface 68 of the cam plate 67, and as the drum continues to rotate the pin 46 will be shifted axially to the position shown in Fig. 2, wherein the remote end 46a of the pin is projecting from the peripheral side surface 28b of the drum. The carry-over pin 46 remains in this axially shifted position during the time that the end 71 thereof traverses the flat high spot on the cam plate 67, and the fractional part of a revolution represented by such duration is sufficient to cause the "minutes" drum 27, which is now coupled to the "seconds" drum by engagement between the pin end 46a and a radial rib 67 to be advanced suffi-

ciently that the detent spring 42 associated with the drum 27 completes a movement of the drum which totals $\frac{1}{60}$ of a revolution, or 36°. This will bring the next or succeeding flat face 31 of the drum 27 to the foremost position. Upon the carry-over pin 46 reaching the end of the flat high spot 70, it will drop off and thus be returned to its normal retracted position by the leaf spring 49 wherein it does not engage any of the radial ribs 67 of the "minutes" drum 27, so that the latter stays at rest temporarily in its newly advanced position.

Repetition of this operation, occurring once each minute, will cause an intermittent advance 15 of the "minutes" drum 27, each time through an arc of 36°, thereby presenting the next flat face 31 of the drum to the foremost position at the front of the clock.

At the time that the character "60" on the 20 "minutes" drum 27 is in position to be shifted to the foremost position, one of the carry-over pins 45 of the said drum will be in the aligning position shown in Figs. 2 and 5, and upon the carry-over pin 46 of the "seconds" drum engaging 25 the cam plate 67, the axial shifting of the said pin will cause the remote end 46a thereof to engage the folded tip portion 57 of the leaf spring 54 carried by the drum 27, and will axially shift the carry-over pin 45. Upon continued movement of the "seconds" drum 28 both 30 of the drums 26 and 27 will thus also be rotated, and the duration of drive between the drum 27 and the drum 26 is such that the detent spring 42 associated with the drum 26 will complete movement 35 of the said drum through a total arc of $\frac{1}{60}$ of a revolution, thereby bringing to the foremost position the next or succeeding surface 30 of the drum. In like manner twice during each revolution of the "tens of minutes" drum 26 the "hour" drum 25 will be advanced through $\frac{1}{60}$ of a revolution.

It will be noted that the folded tip portion 57 of the leaf spring 54 presents a broad flat surface for engagement with the remote or driving end 46a of the carry-over pin 46, and this is an important feature of the invention since it enables the pin 46 to be shifted axially with a gradual movement without danger of the driving end 46a engaging the side edge of the spring 54 or the side of the carry-over pin 45. Such engagement would cause the "minutes" drum 27 to be shifted prematurely and interfere with the proper and correct operation of the mechanism. However, by the provision of a wide flat surface such as the surface presented by the folded tip 57 of the spring 54, the operation of the carry-over mechanism is accurate and reliable under all conditions of use.

Also, by the use of flat leaf springs having folded tip portions which overlie the ends of the carry-over pins, the latter need not be provided with heads, and therefore may be cut from wire stock in a simple and economical screw machine operation.

In accordance with this invention the drums 25, 26 and 27 may be quickly and conveniently shifted by hand when it is necessary to reset the clock. To provide for this, the bottom 16 of the casing 10 is made with an elongate aperture 72 extending along the bottoms of the drums, and a slidable cover plate 73 is mounted over the aperture by means of a pivot screw 74, and is normally yieldably held in place to cover the aperture by a wire spring 75, and by engagement between a lug 76 of the cover plate with

one edge of the aperture 12. When it is desired to have access to the underparts of the drums 25, 26 and 27, it is merely necessary to reach into the aperture 12 in the bottom 16 of the casing and shift the cover plate 73 about the pivot screw 74, whereupon the fingers of the hand may be employed to move either of the drums in whatever direction desired.

To enable the foremost flat surfaces and indicia of the drums to be viewed from the front 10 of the clock casing, the front wall 14 thereof is provided with windows 17 as shown in Figs. 3 through 7.

Variations and modifications may be made within the scope of this invention and portions 15 of the improvements may be used without others.

I claim:

1. In a registering device, a rotary member having indicia; a carry-over pin slidably mounted in the member and located for engagement with an adjacent rotary member when in a predetermined position, the pin being grooved on its side adjacent one end; and an elongate leaf spring secured at one end to the rotary member, the other end portion of the spring being slotted, engaging the grooved portion of the carry-over pin, and normally yieldably holding the latter in an axial position from which it is shiftable to the said predetermined position upon the application of axial pressure, the slotted end portion of the spring being folded back on itself and having an unbroken face overlying and substantially broader than the end of the said pin.

2. In a registering device, a rotary member having indicia; a carry-over member supported for sliding movement in the rotary member and located for engagement with an adjacent indicia-carrying rotary member when in a predetermined axial position, the said carry-over member having a lateral groove at one end; an elongate leaf spring; and means for securing said leaf spring at one end to the said rotary member, the other end of the spring engaging the grooved portion of the carry-over member in such manner as to be freely engageable with and disengageable from said grooved portion by sliding movement when said securing means is released, and normally yieldably holding the latter in a position from which it is shiftable to the said predetermined position upon the application of pressure thereto, said leaf spring when in secured position constituting the sole means for retaining said carry-over member in assembled relation to said first-mentioned rotary member.

3. In a cyclometer-type clock, a rotary member having indicia; a carry-over pin supported for sliding movement in the member and located for engagement with an adjacent indicia-carrying rotary member when in a predetermined axial position, the said pin having a lateral groove adjacent one end; an elongate leaf spring; and means for securing said leaf spring at one end to the said rotary member, the other end of the spring being slotted, engaging the grooved part of the carry-over pin, and the spring normally yieldably holding the pin in an axial position from which it is shiftable to the said predetermined position upon the application of axial pressure, said leaf spring when in secured position constituting the sole means for retaining said pin in assembled relation to said first-mentioned rotary member.

4. For use in a cyclometer-type clock, a rotary member having indicia along its periphery; a carry-over pin supported for sliding movement in the member substantially axially thereof and

extending between opposite end faces of the member, the said pin having an annular groove adjacent one end; an elongate leaf spring; and means for securing said leaf spring at one end to one face of the rotary member with the spring extending along the said face, the other end of the spring being bifurcated, engaging the groove of the carry-over pin, and the spring normally yieldably holding the pin in a predetermined axial position from which it is shiftable upon the application of axial pressure, said leaf spring when in secured position constituting the sole means for retaining said pin in assembled relation to said member.

5. In a cyclometer-type clock, a rotary member having indicia; a carry-over pin slidable in the member and located for engagement with an adjacent indicia-carrying rotary member when in a predetermined axial position, the said pin being grooved on its side at a location adjacent to and spaced from one end; and an elongate leaf spring secured at one end to the said rotary member, the other end of the spring being folded back on itself to form a U and having a slot embracing said one end portion with an edge thereof engaged in said groove, said slot being enlarged at the bottom of the U to permit said one end portion of the carry-over pin beyond the groove to pass through the bottom of the U when said slot is placed in engagement with said groove, the folded portion of the spring being substantially broader than and overlying the end of the pin, and the spring normally yieldably holding the pin in an axial position from which it is shiftable upon the application of axial pressure.

6. In a registering device three rotary members having indicia; a pair of carry-over pins, one slidably mounted in each of two of said members and located for engagement with an adjacent rotary member when in a predetermined axial position, said pins being also mounted for substantial alignment one with the other in a certain relative angular position of the pin-carrying members, the pins being grooved on their sides each adjacent one end; and a pair of elongate leaf springs each secured at one end to one of said pin-carrying members, the other end portions of the springs being slotted and engaging respectively the grooved portions of the pins, the leaf springs normally yieldably holding the pins in axial positions from which they are shiftable to said predetermined positions upon the application of axial pressure, the slotted end portion of one of the springs being folded back upon itself and having an unbroken face overlying and substantially broader than the end of the associated pin, the said face being engageable with the other pin when the latter is in its said predetermined position and said pin-carrying members are in said relative angular position; and means for applying axial pressure to said other pin.
